UNITED STATES PATENT OFFICE.

ELLA F. DOUGHERTY, OF STAUNTON, VIRGINIA.

DESIGN FOR AN ADVERTISING-TABLE.

SPECIFICATION forming part of Design No. 30,140, dated February 7, 1899.

Application filed January 18, 1899. Serial No. 702,589. Term of patent 14 years.

To all whom it may concern:

Be it known that I, ELLA F. DOUGHERTY, a citizen of the United States, residing at Staunton, in the county of Augusta and State 5 of Virginia, have invented and produced a new and original Design for Advertising-Tables, of which the following is a specification, reference being had to the accompanying drawing, forming part thereof, and in which 10 the figure is a perspective view of a table showing my new design.

The leading or material feature of my design consists of the design for the top of the table forming the subject of the accompanying 15 illustration.

The table is provided with the frame A and legs B, which support the top, the latter being provided at its opposite sides and front with the bead C and at its rear edge with the 20 cross bar or plate D, upon which are mounted

the pockets E E, one at each side of the table-top and spaced apart to receive between them the block F, which is grooved to form a pen-rack and recessed for the ink-well. At the front of each pocket E is provided a 25 smaller pocket G, which rests upon the bar or plate D, as shown in the drawing.

In practice the surface of the table-top and the front of the smaller pockets G are of 30 glass.

Having described my invention, what I claim as new, and desire to secure by Letters Patent, is—

The design for an advertising-table, as herein shown and described.

ELLA F. DOUGHERTY.
